UNITED STATES PATENT OFFICE.

WILLIAM H. CADWELL, OF CHICAGO, ILLINOIS.

FOLDING CRATE.

SPECIFICATION forming part of Letters Patent No. 397,894, dated February 19, 1889.

Application filed May 31, 1888. Serial No. 275,598. (No model.)

To all whom it may concern:

Be it known that I, WILLIAM H. CADWELL, a citizen of the United States, residing at Chicago, in the county of Cook and State of Illinois, have invented a new and useful Improvement 5 in Folding Crates, of which the following is a specification.

My invention relates to improvements in folding crates, and more particularly to improvements upon the folding crate heretofore patented to me in Letters Patent No. 328,381, dated October 13, 1885.

My invention consists in the novel devices and novel combinations of parts and devices 15 herein shown and described, and more particularly pointed out in the claims.

In the accompanying drawings, which form a part of this specification, and in which similar letters of reference indicate like parts in 20 all the figures, Figure 1 is a perspective view of a crate embodying my invention. Fig. 2 is an end view; Fig. 3, a section on line 3 3 of Fig. 2. Fig. 4 is a longitudinal section of the crate folded. Figs. 5 and 6 are detail views 25 of the removable partition. Fig. 7 is an enlarged detail view of one of the hinges. Fig. 8 is a detail perspective view of the hinge, and Fig. 9 is a side view of the crate folded.

In said drawings, A represents the bottom 30 of the crate, and a a' the side and end rails, to which the folding sides B B and the overlapping folding ends C C are hinged or pivoted by the hinges b c, respectively. The end rails, a', are wider or higher than the side rails, a, so that the folding ends C may fit 35 properly over the folding sides B of the crate. The hinges b c are of the same construction, and each consists of two staple-form pieces of wire, the free ends of the one being formed 40 into eyes b' c', so as to hinge to the other, and the free ends b² c² of the other piece, b³ c³, being folded around the rails a a' of the bottom, so as to firmly attach the body of the crate to the bottom thereof. The hinges are firmly 45 secured to the rails a a' by staples b⁴ c⁴, and to the posts B' C' of the sides and ends by similar staples. By this means the sides and ends are firmly hinged to the bottom of the crate in a very simple and cheap manner, and 50 the sides and ends are prevented from slipping longitudinally.

The folding ends C are provided at each

extremity with stop-blocks C² C² for the folding sides B to shut or open out against when the crate is erected for use. These stop-blocks C², when the ends C are folded down, as shown in Fig. 9, lie and fit flat and solidly upon the side rails, a, so that no strain can come upon the hinges in case heavy weights 55 are put upon the folded crate. 60

The side and end rails, a a', are secured together and strengthened by staple-form diagonal braces a² at the corners, one prong of the staple being driven into the rail a and one prong into the rail a'. This makes a very 65 cheap and efficient means of tying the side and end rails firmly together.

D is the folding top of the crate, which folds down over the folding ends C C, the same being attached to said folding ends by sliding 70 hinges. These sliding hinges each consist of a wire rod, d, extending longitudinally under one of the slats of the top D and having its end d' folded over the outer end of the top D and its inner end, d², bent at right angles and 75 driven into the lower cross-bar, D', of the top, said wire rod d forming the part of the hinge which is secured to the top D. The wire rod d is also secured in place by staples d³. The wire rod d thus forms a long slot, d⁴, between 80 itself and the slat of the top D, to which it is secured, and in this slot d⁴ fits the wire pin d⁵, constituting the other part of the sliding hinge, which is secured to the folding end C 85 near the top edge thereof. The pin part d⁵ of the hinge is removably secured to the folding end C by means of a staple-form piece of wire, d⁶, having eyes d⁷ for the pin d⁵ to fit in, so that when desired one end of the top D may be entirely detached and swung open, as 90 indicated in Fig. 3. The hinge-pins d⁵ have bent ends d⁸, which, striking against the vertical posts of the folding ends C, prevent the accidental disengagement of the pins from the eyes d⁷. The vertical posts of the folding 95 ends C are furnished with grooves c, to permit the pins d⁵ to be slipped out when the bent ends d⁸ of said pins are turned upward.

The lower cross-bars, D', of the top fit inside the folding sides B B of the crate when the crate is erected for use, as is clearly shown in Fig. 1, and thus serve as stops or braces to hold the sides B B in position.

It will be understood that there is sufficient

bend or elasticity to the top D to permit the folding sides B B to be opened out or erected under the cross-bars D' D'.

The cross-bars D' of the top serve not only as stops for the sides B B to abut against when the crate is erected, but also as stops for the folding ends C C to abut against when the crate is folded down, as is clearly shown in Fig. 4 of the drawings. The sliding hinged top D is thus prevented from slipping lengthwise on the folded crate, and all danger of its being therefore broken is avoided.

The sliding hinged top D is provided with one loose or sliding slat, D², to form an opening for putting the poultry in or taking it out. This movable slat D² is held in place by a wire latch, E, hinged by staples e to the adjoining longitudinal slat of the top and fitting in a suitable hole or opening in the movable slat D². In this way the latch E is made to lie flat upon the slats of the top D and below the upper cross-bars thereof, so as to be protected from injury.

The end rails, a' a', are each furnished with wire-hinged bail-form catches a³, to engage the ends of the movable slat D² of the top when the crate is folded, so as to securely lock or fasten the folded bottom, sides, ends, and top of the crate together, and thus prevent danger of injury in shipment. The hinged catch E serves to lock the movable slat D² in place when the crate is folded as well as when it is erected. The wire catches a³ are hinged to the rails a' by staples a⁴.

F is a movable partition extending across the crate at its middle to prevent the fowls injuriously piling up on each other when the crate is tilted. The top slat of this partition F is furnished with notches or hooks f, which engage the cross-pins f' in the slotted blocks or guides f², which are secured to the folding sides B B. The partition F thus serves also to brace the sides B B and tie them together, so that they cannot spring out at the middle. The partition F lies flat upon the bottom of the crate when the crate is folded, and is thus inclosed by the folding sides B B, so that it cannot get out or become lost. After the crate is erected the partition is readily put in place by simply slipping the ends of its slats into the grooves of the guide-blocks f².

The partition F is of less height than the crate, so that the partition may be readily set up in the crate without raising or removing the cover of the crate.

I claim—

1. The folding crate consisting in the combination of a bottom, A, with folding sides B

B, folding ends C C, and folding top D, having sliding hinges connecting the same with 60 said ends C C, and provided with under cross-bars, D² D², for the folding ends C C to abut against when the crate is folded, substantially as specified.

2. In a folding crate, the combination, with 65 bottom A, having side and end rails, a a', of folding sides B B, wire staple-form hinges b b' b² b³, uniting said parts, the free ends b² of the wire hinge part b³ being folded around said rails a, folding ends C C, and wire staple-form hinges c c' c² c³, uniting said parts, the free ends c² of the wire hinge-piece c³ being folded around said rails a', substantially as specified.

3. The combination, with the bottom of a 75 folding crate, of a folding side and a wire staple-form hinge of two pieces, b and b³, said part b having eyes b' at its free ends and the free ends b² of the part b³ being folded around a rail on the bottom of said crate, substantially as specified.

4. The combination, with bottom A, of folding sides B B, folding ends C C, folding top D, wire hinge-rod d, extending longitudinally under one of the slats of said top to form a 85 slot for the sliding hinge-pin to fit in, and a removable hinge-pin, d², secured to said folding end C near the top edge thereof, substantially as specified.

5. In a folding crate, the sliding hinged top 90 D, having movable slat D², and upper and lower cross-bars, between which said slat D² slides, and provided with a wire hinged catch, E, consisting of two right-angled portions, one of which is stapled to an adjoining slat and 95 the other of which is provided with a downwardly-bent end, substantially as shown, to enter a hole in said movable slat D², and staples e, substantially as specified.

6. The combination, with bottom A, having 100 side and end rails, a a', of folding hinged sides B B, folding hinged ends C C, top D, having sliding hinges connecting the same at both ends with said ends C C, partition F, formed of upright posts and cross-slats, with 105 spaces between, and having hooks f, pins f', and slotted guides f² f² secured to said sides B B, said partition being of less height than the crate, so that said partition may be set up or taken down without removing said folding 110 top D, substantially as specified.

WILLIAM H. CADWELL.
